COUNTER TOP WATER FILTER

Thomas R. Bertrand, Addison, Ill., assignor to P.F.C.
Financial Corporation, Elgin, Ill.

Filed June 7, 1973, Ser. No. 367,980

Term of patent 14 years

Int. Cl. D23—01

U.S. Cl. D23—4

FIG. 1

FIG. 4

FIG. 2

FIG. 3

FIG. 5

FIG. 1 is a top plan view of a counter top water filter embodying my new design;

FIG. 2 is a bottom plan view thereof;

FIG. 3 is a front view thereof;

FIG. 4 is a rear view thereof; and

FIG. 5 is an elevational view taken from one side thereof, the opposite side being a mirror image of the side shown.

I claim:

The ornamental design for a counter top water filter, as shown and described.
